TURN INDICATOR FOR AUTOMOBILES

August F. Pfingsten, Rock Rapids, Iowa

Application January 12, 1938, Serial No. 184,572

1 Claim. (Cl. 177—327)

My invention relates to a turn indicator.

An object of my invention is to provide a turn indicator which is mounted in such a position on the vehicle that it can not fail to be seen from all points.

A further object of my invention is to provide a device of this character which presents a neat and symmetrical appearance in line with the presentday design of automobiles.

10 A further object of my invention is to provide a device which is readily seen in strong sunlight or at night.

15 A further object of my invention is to provide an apparatus of this type which works smoothly and instantaneously in the operation of suitable switches and the like.

A further object of my invention is to provide a turn indicator which is combined with a suitable radio antenna.

20 A further object of my invention is to provide a device of this character, which in inoperative or forward position will not sway due to wind pressure and will remain in fixed position when in such inoperative position.

25 A further object of my invention is to provide means for efficiently swinging the indicating portions of the apparatus to either side.

30 A further object of my invention is to provide a stop signal which functions cooperatively with the indicator signal.

A further object of my invention is to provide a weather resisting indicator which is simple in construction.

With these and other objects in view, my invention consists in the construction, arrangement and combination of the various parts of my device, whereby the objects contemplated are attained, as hereinafter more fully set forth, pointed out in my claim, and illustrated in the accompanying drawings, in which:

Figure 1 is a side elevation of the indicator mounted upon the top of a vehicle.

Figure 2 is a plan view of the same.

Figure 3 is a sectional view taken substantially along the lines 3—3 of Figure 2.

Figure 4 is a view taken substantially along the lines 4—4 of Figure 3.

Figure 5 is a sectional view taken along the lines 5—5 of Figure 3.

Figure 6 is a modified form of the device.

Figure 7 is a wiring diagram used in the device.

Figures 8 and 9 are side and forward views of the switch.

Figure 10 is a modification showing the antenna attachment, and

Figure 11 is a diagrammatic view showing the device explaining its comparative advantages at street intersections.

I have used the character 10 to indicate generally an automobile top which naturally is at the uppermost part of the vehicle. The principal object of my invention is to position my device on the top of the vehicle on the center thereof and slightly towards the rear. This provides the best location for indicating to drivers, in any position of the same on other highways or streets, stops or turns.

My invention employs the use of a concave 15 chamber 11 which is substantially semi-spherical in form and which is attached by means of the rim 12 to the top of the vehicle 10. The chamber 11 receives at 13 a shaft 14 which extends into the portion 15. Attached to the portion 15 and 20 above the top of the chamber 11 is a further cover member 16 which includes the arcuate side walls 17 which follow substantially the contour of the chamber 11 and extend downwardly a slight distance thereon. Attached to the member 16 is the indicating member 18 which is hollow throughout as shown in Figure 5 and which terminates in the arrow portion 19. The member 18 includes the transparent mica or Celluloid 20 which can be colored red or any other suitable 30 color. The member 18 is substantially circular throughout its section but at the arrow portion 19 terminates in a flattened formation as at 21 (see Figure 2).

The member 18 extends rearwardly and terminates in a smooth and symmetrical line at 22 with the top member 16 and the arrow formation terminates at 23. Extending forwardly from the chamber 11 is the box like or rectangular member 24 which extends to the rear 40 and attached within the member 24 is the red glass window 25. Attached rearwardly of the window 25 is the concave reflector 26 to which is attached the socket 27 into which is received the bulb 28. The member 24 includes the forwardly 45 extending sides 29 which extend a substantial distance from the glass member 25 to provide means for shading the same from the sunlight.

A suitable wire lead 30 is coiled at 31 and passes upwardly through the hollow portion 32 50 in the shaft 14. The wire 30 is attached to the sockets 33 which are attached to suitable brackets 34 which in turn are attached at the top of the member 18. Electric light bulbs 35 are attached within the sockets 33. Attached to the 55

shaft 14 at 36 is the gear member 37 which includes the gear teeth 38 which are situated on approximately one-half of the circumference thereof.

- A further transverse member 39 includes a series of teeth 39a adapted to mesh with the teeth 38 and the member 39 is rectangular in shape and terminates in the left hand circular iron plunger 40 and the right hand plunger 41. 10 The plungers 40 and 41 are received within hollow tubes 42 and 43 which are positioned centrally within the electric solenoid coils 44 and 45. The coils 44 and 45 are attached by means of the flanges 46 and 47 to the base 48 of the device. 15 A pair of compression springs 49 and 50 are received within the circular tubes 42 and 43 and the compressive strength of these springs are fairly evenly balanced. A further solenoid 51 which includes the tube 52 receives an iron plunger 53 which also is seated upon a further compression spring 54 which spring is located within the tube 52. At the end of the plunger 53 is located the male slightly tapered extremity 55 which is received within a cavity 56 which is 20 cut out of the member 39. A slight amount of clearance is left between the member 55 and 56. The lower end of the shaft 14 is suitably journaled on the base 48.

The device is controlled by means of the switch 30 57 which includes the toggle arm 58 having the handle 59. The arm 58 pivots at 60 and extends into the contacting portion 61 which is connected at 62 to the lead 63 which is connected as shown in the circuit of Figure 7. Further contacts 64, 65, 66 and 67 are situated in the switch 57. The various members of the device are connected to the battery 68 and the various other portions of the circuit are shown therein, showing the connections of the same, to the various responsive elements. The operation of the device will now be explained.

Normally the indicating arrow 18 is in the forward position or in the direction the car is moving and in the direction shown by the arrow 69 in Figure 4. The plunger 53 is then in its forward position with the member 55 received within the female portion 56. The arrow is thereby locked firmly against relative movement due to wind or other causes and will not be 50 swung out of position.

Assuming that a left turn is to be made, the toggle switch handle 58 is thrown over to the left by the operator. This establishes contact from the lead 63 and across the contacts 66 and 45 67, the leads from the contact 66 lighting the light bulbs 35, the rear stop light bulb 28, and at the same time actuates the small solenoid 51 which causes retraction of the plunger 53 therein.

60 This causes the release of engagement between the male member 55 and the female member 56 so that the device is ready for swinging movement. At the same instant contact is established at 67 which by examination of the diagram will show that the right hand solenoid 45 is actuated. This then throws the plunger 41 into the solenoid 45 and correspondingly rotates the gear 37 in the direction of the arrow 70 which in turn swings the shaft 14 in the corresponding 70 direction and carries the arrow member 18 around to indicate a left turn. The tapered formation of the engaging members 55 and 56 prevent jamming of the device and also since the small plunger 53 is of less mass and of a smaller 75 distance from the other parts it will move quicker

which will cause the aforesaid release slightly ahead of the larger plunger action although this feature will not be necessary for the effective operation since the tapered sides of the plunger as well as instant action will cause a positive retraction action. 5

Correspondingly to indicate a right turn, the toggle switch handle as shown in Figure 8 is thrown to the right which in turn establishes contact across the contact 64 which also lights 10 up the bulbs 35, which actuates the solenoid 51 and which actuates the rear bulb 28. At the same time, through the contact at 65 the left hand solenoid 44 is actuated and the arrow member 18 will swing in the direction of the 15 arrow 71 as shown in Figure 4 indicating a right turn.

The coiled wire 31 which leads to the bulbs 35 prevents undue strain on the same due to its helical formation as the arrow member is swung 20 from left to right. It will be seen that upon either left or right turns that the rear bulbs 28 will be lighted which will give a further signaling effect to the driver in the rear although the same is not really necessary during daylight conditions 25 since the arrow 18 will be plainly visible at any point. However, the lighting of the bulb 28 which will be visible through a red or other glass 25 will serve to accentuate the effect of visibility especially during cloudy days or at night and due 30 to the hooded features of the hood 29 will assist the action during lighter conditions. The lighting of the bulb 28 simultaneously with the operation of the arrow 18 also assists in indicating a turn since the vehicle usually slows down 35 before such turning.

However, as aforesaid for daylight driving conditions, the visibility of the arrow is quite prominent and it can be made of a silver color or any other color readily visible. The Celluloid 20 of the arrow can be made of red color or any other suitable color so that for night driving the indicator is readily visible and even though the same effects are obtained during the day time they will not be necessary although these features would materially assist the visibility in certain cases. The light 28 can also be connected into the circuit with the lead 72 which is actuated by the usual brake contact 73 so that the bulb 28 serves as a stop signal also. 50

After turning, the operator throws the handle 58 to neutral position and due to the compression of the springs within the solenoid and the resulting mass of the plunger with the momentum imparted thereto will insure that the bar 39 will be thrown back past the center point and since the plunger 53 is already released the male member 55 thereof will snap into engagement with the female portion 56 thereby locking the arrow in forward or neutral position. 60

Figure 6 illustrates a modification wherein the arrangement is supported on a bracket 74 which is attached at 75 to the side of a truck or other higher vehicle which may necessitate a side 65 mounting although the principal use of the device is intended for the top of the automobile. The modification shown in Figure 6 is operated in the same manner as previously described.

In referring to the switch as shown in Figures 8 and 9, it will be observed that the contacts are mounted upon an insulating member 76. Figure 11 shows the use of the device at street intersections and explains the use of the device, showing how it is readily visible from all points where 70

other drivers may be located. The lines of vision are indicated by the arrows 11.

Figure 10 illustrates a slightly modified form of the device which includes an aerial or antenna attachment. Present day vehicles use such antennae for the use of radios and which antennae are usually positioned on the top of the vehicle. The foregoing structure is the same for the turn indicator with the exception, however, that I attach to the arrow indicator at 18, an insulator 19 which includes the bracket 80, which bracket firmly holds the antennae wire 90. The wire 90 can curve downwardly at 91 and extends rearwardly to the approximate point 92 where it is connected to an insulator wire lead 93, which passes through a suitable opening in the lower point of the indicator arrow 18 and which in turn passes into the arrow and downwardly through the shaft 14 in the same manner as the wire 30.

The looping of the wire lead as shown prevents moisture from entering into the arrangement since it is at a lower point. It will be noted from this construction that the antenna can be mounted directly upon the signaling unit without destroying the efficiency of the arrangement and that it also provides a desirable and suitable mounting for the aerial. Normally the arrow will be pointing forwardly in the direction of the vehicle as shown in Figure 10 and will be in a normal position and will only be positioned transversely during the turning operation. The appearance is also symmetrical with the design of the indicator and connections can be made in any suitable manner.

It will now be seen that I have provided a turn indicator which indicates a left or right turn or stop, which is mounted in such a position on the vehicle that it can be seen from all points, which has a neat and symmetrical appearance, 5 which can be seen readily in either strong sunlight or at night, which works smoothly and instantly, which can be kept locked in forward position, and which can be manufactured at a reasonable cost. It will be also seen that I have 10 provided a turn indicator which includes a suitable radio antenna connection attached thereto.

Other advantages are readily apparent from the description.

Some changes may be made in the construction 15 and arrangement of the parts of my invention without departing from the real spirit and purpose of my invention, and it is my intention to cover by my claim any modified forms of structure or use of mechanical equivalents which may 20 be reasonably included within their scope.

I claim as my invention:

A turn indicator for automobiles comprising a substantially semi-spherical hollow member, an enclosing covering member adapted to follow the 25 upper contour of said substantially semi-spherical member, an arrow member integrally formed with said covering member, means for rotating said covering member to rotate the arrow to selected position, a shaft attached to said covering member and rotatable within the upper portion of said semi-spherical member, said arrow member providing a covering at the top of said shaft.

AUGUST F. PFINGSTEN. 35
